UNITED STATES PATENT OFFICE.

THOMAS BARNABY, OF MIDDLETOWN, OHIO.

DESIGN FOR A DANCING TOY.

58,285.

Specification for Design.

Patented July 5, 1921.

Application filed January 17, 1921. Serial No. 438,031. Term of patent $3\frac{1}{2}$ years.

To all whom it may concern:

Be it known that I, THOMAS BARNABY, a citizen of the United States, residing at Middletown, in the county of Butler and State of Ohio, have invented a new, original, and ornamental Design for a Dancing Toy, of which the following is a specification, reference being had to the accompanying drawing, forming part thereof.

Figure 1 is a perspective view of a dancing toy showing my new design; and Fig. 2 is a top plan view thereof.

I claim:

The ornamental design for a dancing toy, as shown.

THOMAS BARNABY.
